UNITED STATES PATENT OFFICE

143,327

DESIGN FOR A CAN OPENER

Michael J. La Forte, Park Ridge, Ill., assignor to
Vaughan Novelty Mfg. Co., Chicago, Ill., a cor-
poration of Illinois

Application November 16, 1944, Serial No. 116,363

Term of patent 14 years

(Cl. D22—2)

To all whom it may concern:

Be it known that I, Michael J. La Forte, a citizen of the United States, residing at Park Ridge, in the county of Cook and State of Illinois, have invented a new, original, and ornamental Design for a Can Opener, of which the following is a specification, reference being had to the accompanying drawing forming part thereof.

Figure 1 is a top perspective view of the can opener of my invention;

Figure 2 is a bottom perspective view; and

Figure 3 is a side elevational view.

The essential feature of my design resides in a can opener of the configuration shown having a rib comprising two spaced apart parallel portions of different length converging and united at one end as best illustrated in Fig. 1 of the drawing.

I claim:

The ornamental design for a can opener, as shown and described.

MICHAEL J. LA FORTE.
